UNITED STATES PATENT OFFICE

HENRY G. HILLARD, OF REGINA, SASKATCHEWAN, CANADA, ASSIGNOR OF FIFTY-ONE
ONE HUNDREDTHS TO IRA H. BOWMAN, TRUSTEE, AND ONE-FIFTH TO IRA H.
BOWMAN, OF REGINA, SASKATCHEWAN, CANADA

DESIGN FOR PAPER FABRIC

Application filed October 22, 1932. Serial No. 45,507. Term of patent 7 years.

To all whom it may concern:

Be it known that I, HENRY G. HILLARD, a subject of the King of England, residing at Regina, in the Province of Saskatchewan, Dominion of Canada, have invented a new, original, and ornamental Design for Paper Fabric, of which the following is a specification, reference being had to the accompanying drawing, wherein

The figure is a plan view of a piece of paper fabric showing my new design.

I claim:

The ornamental design for paper fabric substantially as shown.

HENRY G. HILLARD.
